US0D1047268S

(12) United States Design Patent (10) Patent No.: US D1,047,268 S
(45) Date of Patent:  *Oct. 15, 2024

(54) FRAME FOR LIGHT

(71) Applicants: Yuree Hwang, Singapore River (SG);
Mark A. Zeh, Munich (DE)

(72) Inventors: Yuree Hwang, Singapore River (SG);
Mark A. Zeh, Munich (DE)

(*) Notice: This patent is subject to a terminal disclaimer.

() Term: 15 Years

(21) Appl. No.: 29/768,352

(22) Filed: Jan. 28, 2021

(51) LOC (14) Cl. 26-04

(52) U.S. Cl.

USPC D26/113; D26/141

(58) Field of Classification Search

USPC D26/72, 80, 81, 83, 88, 143–144, 138,
D26/141

CPC F21S 8/06; F21S 8/061; F21S 8/063; F21S
8/065; F21S 8/066; F21S 8/068
